UNITED STATES PATENT OFFICE

129,326

DESIGN FOR A WATCH BRACELET

William Forstner, Irvington, N. J., assignor to Forstner Chain Corporation, Irvington, N. J., a corporation of New Jersey

Application May 6, 1940, Serial No. 92,177

Term of patent 14 years

To all whom it may concern:

Be it known that I, William Forstner, a citizen of the United States, residing at Irvington, in the county of Essex and State of New Jersey have invented a new, original, and ornamental Design for a Watch Bracelet, of which the following is a specification, reference being had to the accompanying drawing, constituting a part thereof.

Fig. 1 is a plan view of a watch bracelet showing my new design;

Fig. 2 is a side view thereof; and

Fig. 3 is an enlarged sectional view taken on line 3—3 of Fig. 1.

I claim:

The ornamental design for a watch bracelet, substantially as shown.

WILLIAM FORSTNER.
